UNITED STATES PATENT OFFICE.

GEORGE B. THOMAS, OF BRIDGEPORT, CONNECTICUT, ASSIGNOR TO BRYANT ELECTRIC COMPANY, A CORPORATION OF CONNECTICUT.

LAMP HOLDER.

Application filed April 27, 1918. Serial No. 231,113.

To all whom it may concern:

Be it known that I, GEORGE B. THOMAS, a citizen of the United States of America, residing at Bridgeport, in the county of Fairfield and State of Connecticut, have invented a certain new and useful Improvement in a Lamp Holder, of which the following is a specification.

My invention relates to a lamp holder for 10 sockets of the Edi-Swan type, and particularly to a device for steadyng the lamp in its socket, the object of my invention being to provide a simple and readily operated device by which the lamp may be prevented from 15 rocking on the axis of its customary holding pins.

In the accompanying drawing,

Fig. 1 is a broken side elevation of a lamp socket of the Edi-Swan type, showing a 20 lamp in position therein and engaged by the holding device to which the invention relates;

Fig. 2 is a partial side elevation thereof;

Fig. 3 is a broken side elevation showing 25 the holding ring in the position which it assumes on the insertion of a lamp into the socket;

Fig. 4 is a section on the line 4—4, Fig. 2;

Fig. 5 is a drop perspective of the shade-holding ring and the lamp-holding ring; 30 and

Fig. 6 is a plan of the lamp base.

Lamps of the Edi-Swan type comprise a base having a metal shell 10, to which the 35 globe 11 is sealed and from which project the studs 12, by means of which the lamp is held in a socket. At the entering end of the shell 10 is secured an insulating button 13, carrying the lamp terminals 14 and 15, with 40 which cooperate the corresponding terminals of the socket. The socket here shown for cooperating with a lamp of this type, has a casing of the same general construction as that shown in my prior Patent 1,239,817 and comprises a cap 16 latched to the shell 17 the other end of which is extended by a sleeve 18 having a flange 19 which overlies the inturned lower edge 20 of the shell 17 and rigidly secured in position by the lock 45 nut 21, which screws upon the threaded area 22 of the sleeve and may be utilized to hold a lamp shade, as indicated in my prior patent above referred to. At its outer end, the sleeve 18 is of slightly reduced diameter to 55 more closely fit telescopically over the enter-

ing end of the shell 10 of the lamp base, and is provided on opposite sides with bayonet slots 23, with which the studs 12 of the lamp base engage. The spring stud terminals 24 and 25 (Fig. 4) of the socket, which cooperate with the terminals 14 and 15 of the lamp base, are carried by the insulating body 26 of the socket and project into the chamber formed by the sleeve 18. While there is a general correspondence between 60 the diameter of the entering end of the lamp base 10 and the internal diameter of the sleeve 18 at its outer end, there is nevertheless considerable play between these parts, with the result that the lamp rocks on the 65 studs 12 after the lamp is in position. This not only augments the flicker of the light emitted by the lamp when the latter is subject to vibration, but is apt to cause injury to the lamp filament and thus shorten the 70 life of the lamp, and, furthermore, adds to the insecurity of the bayonet slot fastening. To avoid this defect, I have now provided 75 means carried by the lamp socket and engaging the lamp in its inserted position to hold the latter rigid and prevent its rocking on the axis of its studs 12.

This lamp-holding device in the form here shown comprises a ring 27, internally threaded at 28 to screw upon the threaded area 22 of the socket sleeve 18. At the opposite end of the ring a neck 29 is formed by inwardly offsetting the wall of the ring a sufficient distance to conform the internal diameter of the neck 29 substantially to 80 that of the entering end of the shell 10, so that when the ring is screwed outward on the sleeve 18, the neck 29 of the sleeve engages the shoulder 30 of the lamp base. At opposite points, slots 31 are cut in the 85 neck end of the holding ring 27 to permit the passage of the studs 12 on the lamp base into the bayonet slots 23 in the sleeve 18, and these slots 31 are extended across the offset and into the body of the sleeve. It 90 will be noted that an annular chamber 32 is afforded between the body of the sleeve 18 and the inner wall of the holding ring 27 to accommodate the outer ends of the 95 studs 12, which, in inserted position, project through the bayonet slots 23 beyond the outer face of the sleeve. This clearance between the holding ring 27 and the sleeve 18 permits the ring to be rotated 100 after the lamp has been inserted in the 105

socket. A knurled area 33 may be formed on the ring to facilitate its rotation.

The operation of this device is readily understood. In order to permit the insertion of the lamp in the socket, the holding ring 27 is screwed down toward the socket shell 17 to get it out of obstructing position. When turned sufficiently far down, it is then brought to a position in which its slots 10 31 register with the bayonet slots 23 in the sleeve 18. The lamp is now inserted by passing its base into the sleeve 18 with the studs 12 in register with the slots 31 and 23, and rotating it to bring the studs into engagement 15 with the locking branches of the bayonet slots 23. The holding ring 27 is then screwed outward until the end of its neck 29 bears firmly against the shoulder 30 of the lamp base 10. In this position 20 it not only holds the lamp against oscillation on the studs 12, but also locks the studs in engagement with the offset branch of the bayonet slot 23 and prevents any possibility 25 of the lamp's accidental escape from the socket.

Various modifications in detail of construction and arrangement will readily occur to those skilled in the art which do not depart from what I claim as my invention. 30 I do not limit the application of this locking device to sockets of the particular construction shown, since it may obviously be used with any type of socket having the necessary threaded area or equivalent means 35 for engagement with the locking ring.

I claim:—

1. A lamp socket having a casing element slotted to afford a bayonet joint connection with a cooperating lamp and having a 40 threaded area, in combination with a screw ring threaded on said area and movable into engagement with a shouldered lamp base after the establishment of said bayonet joint connection to hold the lamp against 45 vibration with relation to the socket, said

ring surrounding the bayonet joint but being spaced from said casing element at the bayonet joint to clear one of the bayonet joint members and permit the rotation of the ring around said joint, but constricted 50 at its outer end to afford an end engagement with the lamp base.

2. A lamp socket having a casing element slotted to afford a bayonet joint connection with a cooperating lamp and having a 55 threaded area, in combination with a screw ring threaded on said area and movable into end engagement with a shouldered lamp base after the establishment of said bayonet joint connection to hold the lamp against vibration with relation to the socket, said ring surrounding the bayonet joint, and being inwardly offset and slotted at its lamp engaging end to permit the passage there-through of the bayonet joint member on 60 the lamp end.

3. The combination with an electric lamp having a shouldered base with lateral securing studs, of an electric lamp socket having a lamp-supporting casing element 70 comprising a threaded sleeve bayonet-slotted at its lamp-receiving end to accommodate said studs, and within which the end of the lamp is socketed in inserted position, together with a shouldered ring screwed on 75 said sleeve and radially slotted to accommodate the studs on the lamp base, but free to rotate on said casing element when the lamp is in inserted position, the outer end of said sleeve being of reduced diameter 80 and having an end engagement with the shoulder of the lamp base when said ring is moved into lamp-engaging position.

4. In a construction as specified in claim 3, radial slots in the lamp-engaging ring extending into the shouldered area of said ring.

In testimony whereof I have signed my name to this specification.

GEORGE B. THOMAS.
